STARTING DEVICE FOR EXPLOSION-ENGINES.

No. 813,959.

Specification of Letters Patent.

Patented Feb. 27, 1906.

Application filed April 12, 1905. Serial No. 265,210.

To all whom it may concern:

Be it known that I, VICTOR ERDMENGER, a subject of the German Emperor, and a resident of Essen-on-the-Ruhr, Germany, have 5 invented certain new and useful Improvements in Starting Devices for Explosion-Engines, of which the following is a specification.

The present invention relates to a starting device for double-acting four-cycle explosion-engines, and in particular to the kind of starting devices in which compressed air is used for starting such explosion-engines. As commonly known, the working of such an engine during the explosion operation takes place 15 according to the diagrams Y' Y². (Shown in Figure 4 of the accompanying drawings.) The diagram Y' relates to the front part of the cylinder, while the diagram Y² relates to the rear part of the cylinder. The 20 vertical lines I to IV indicate the limits of the four phases of the four-cycle operation. Each of the phases I to II, II to III, and so on corresponds to one stroke of the working piston. In the diagram Y' of the front part of the cylinder the explosion takes place at the point I. The phase I to II indicates the expansion, the phase II to III the exhaust, the phase III to IV the suction, and the phase IV to I the compression. The phases of the working in the 25 rear part of the cylinder shown in the diagram Y² follow one another in the same order of succession; but, as a comparison of the two diagrams shows, the phases in the diagram Y² lag one phase behind the phases in the diagram Y', so that in the diagram Y² the moment of the explosion coincides with the point II, while the expansion takes place in the phase II to III, the exhaust in the phase III to IV, the suction in the phase IV to I, and the compression in the phase I to II. The starting, 30 too, has to take place in four phases in such a manner that compressed air is introduced into the cylinder parts in the phases in which explosion or expansion would take place if the operation was caused by explosion. Thus the 35 compressed air would in the present instance be introduced into the front part of the cylinder in the phase I to II and into the rear part of the cylinder in the phase II to III. According 40 to the above remarks the working proceeding in the front and in the rear part of the cylinder when the engine is started takes place corresponding to the diagram X' X².

(Shown in Fig. 4.) The introduction phase I to II of the starting - diagram X' for the 55 front part of the cylinder is succeeded by exhaust in the phase II to III in the same manner as by explosion operation. The succeeding two phases III to IV and IV to I differ from the corresponding phases of the explosion 6c operation in so far as there cannot be any suction and compression, because the gas and air pipes for the inlet-valve as used by explosion operation have to be closed during the starting. The suction phase and the 65 compression phase are therefore in the starting replaced by a low pressure in the phase III to IV, which in the succeeding phase IV to I is again brought back to atmospheric pressure. The phases of the working diagram 70 X² of the rear part of the cylinder follow one another in the same order of succession as those of the diagram X'; but they lag one phase behind, so that the introduction of compressed air takes place in the phase II to III, 75 the exhaust in the phase II to IV, the low pressure in the phase IV to I, and the return to atmospheric pressure in the phase I to II.

In the accompanying drawings one embodiment of the improved starting device is 80 shown by way of example.

Fig. 1 is a diagrammatic view of the starting device and part of the working cylinder, partly in section. Fig. 2 is a view corresponding to Fig. 1 with altered position of the slide-valve. Fig. 3 is a view corresponding to Fig. 1 with still another position of the slide-valve. Fig. 4 is a diagrammatic illustration of the phases, as fully explained above. Fig. 5 is a diagrammatic view showing the starting device on a reduced scale and also the cylinder and the source of compressed air, and Fig. 6 shows a detail.

A slide-valve A is arranged to slide in a cylindrical hollow space 1 of a housing B, arranged on the working cylinder C, having piston K. The upper and lower ends of the valve A fit tightly the wall of the space 1 by means of packing-surfaces a' a², while the central part of the valve is reduced so as to 95 form an annular space 2. The slide A is by means of a link D connected to one arm E of a controlling-rod E E', which is pivoted in a support b', projecting from the housing B. The other arm E' of the controlling-rod terminates in an eye member e², in the perfora- 100 105

tion of which is journaled the pivot of a roller F. The roller F engages the cam-groove g' of a controlling-disk G, which is arranged on the controlling-shaft H of the engine. The controlling-disk G is through the medium of any suitable means, such as a coupling-sleeve L, (see Fig. 6,) connected with the controlling-shaft H and with a fixed part of the engine in such a manner that it during the operation may be coupled to either of said parts, so as to either rotate with the shaft H or remain stationary. On the drawings the controlling-disk G is divided into four quadrants I to II, II to III, III to IV, and IV to I. In the quadrants III to IV and IV to I the curved groove g' extends concentric with the controlling-shaft H, while in the quadrant I to II the curve is bent inwardly and in the quadrant II to III the curve is bent outwardly.

Passages 3, 4, and 5 provide for communication between the annular space 2 and annular chambers 6, 7, and 8. The annular chamber 6 communicates with the perforation of a projection b², to which is secured the conduit J for the compressed air. The annular chamber 7 communicates with the front part of the working cylinder through the medium of channels 9 and c', and the annular chamber 8 communicates with the rear part of the working cylinder through the medium of channels 10 and c².

The controlling-shaft H is in the usual manner driven from the crank-shaft at the ratio of two to one, and each half-rotation of the crank-shaft or each stroke of the working piston will therefore effect one-fourth of a rotation of the controlling-disk.

In Fig. 1, which illustrates the intermediate position of the valve A, the annular space 2 communicates with the conduit J for the compressed air. The flow from the compressed-air source M may be regulated by means of a valve N. The passages 4 and 5 are closed by the packing-faces a' and a² of the valve A, so as to prevent the compressed air from passing from the space 2 to the working cylinder. The valve A remains in the intermediate position for so long a time as the roller F is in engagement with any point of the groove parts III to IV and IV to I that are concentric with the controlling-shaft. When the controlling-disk G rotates with the controlling-shaft H in the direction of the arrow z, Fig. 1, the roller F will enter into engagement with the part I to II of the curved groove. This causes the arm E' of the controlling-lever to ascend while the arm E descends, and the valve A therefore moves downwardly. When the roller F reaches the most inwardly-bent place of the curved groove, the valve assumes the position shown in Fig. 2, in which only the passages 5 are closed, while the passages 3 and 4 communicate with one another through the annular space 2. Com-

pressed air can therefore pass from the annular space 2 through the passages 4 to the annular chamber 7, from where it passes through the channels 9 and c' and a suitable valve d' to the front part of the working cylinder. (Phase I to II of the diagram X'.) By the further turning of the controlling-disk the valve A reverses its direction of movement and the face a' closes the passages 4. When the point II of the groove reaches the roller F, the valve reassumes the position shown in Fig. 1, and when the outwardly-bent part II to III reaches the roller the slide moves upward, thereby opening the passages 5. If the most outwardly-bent place of the curved groove has reached the roller F, the valve assumes the position shown in Fig. 3, in which the compressed air can pass by the way 2, 5, 8, 10, and c², d² to the rear part of the working cylinder. (Phase II to III of the diagram X'.) In the further course of the turning of the controlling-disk the valve A again reverses its direction of movement and the face a² closes the passages 5. From the point III of the groove 90 the valve reassumes the intermediate position shown in Fig. 1 and remains in such position during one-half rotation of the controlling-disk. (Phases III to IV and IV to I of the diagrams X' and X'.) In the point I 95 of the curved groove g' the play starts over again. It will thus be seen that the introduction of compressed air into the front part of the cylinder takes place in phase I to II and that the compressed-air conduit is closed 100 with regard to the front part of the cylinder in phases II to III, III to IV, and IV to I. The introduction of compressed air into the rear part of the cylinder takes place in phase II to III, and the compressed-air conduit is closed 105 with regard to the rear part of the cylinder in phases III to IV, IV to I, and I to II. The working proceeding after the closing of the compressed-air conduit in phases II to III, III to IV, and IV to I with regard to the 110 front part of the cylinder and in phases III to IV, IV to I, and I to II with regard to the rear part of the cylinder must necessarily take place in the manner shown in the diagrams X' X', and it is therefore evident that 115 an explosion-engine provided with the improved starting device works as a four-cycle one.

When it is desired to start the engine, the grooved disk is coupled to the controlling-shaft. The fly-wheel is then turned until the grooved disk assumes a position in which the roller F engages part I II of the disk, thereby causing compressed air to pass to the front part of the cylinder. From this moment the engine is driven automatically by means of the compressed air. To pass over to the explosion operation, the grooved disk is uncoupled from the controlling-disk, which then turns in the disk without carrying the 130

same along. The disk is thereupon turned to and secured in a position in which the roller F engages with any point of the part of the groove g that is concentric with the controlling-shaft, in which position the compressed air is cut off by the valve A, Fig. 1. Upon the opening of the gas and air conduit for the inlet-valve used for the explosion and upon making connection for the sparking device the engine works with explosion operation.

Having thus described the invention, what is claimed is—

1. In a compressed-air starting device for double-acting four-cycle explosion-engines, means constructed to open communication for the compressed air first to one end of the cylinder and then to the other end of the cylinder and then to close communication with both ends of the cylinder during the succeeding reciprocation of the piston, and means for connecting the means first named to the driving member of the engine to be started, whereby, when the air is admitted to one end of the cylinder, the subsequent movements follow automatically.
2. In combination with a double-acting four-cycle explosion-engine and a suitable source of compressed air, a valve movable to open communication for the compressed air

with first one end of the cylinder and then the other end of the cylinder and then movable to a position to cut off said air-supply from both ends of the cylinder, and a cam adapted to be driven by the engine, and constructed to impart the two opening movements during successive strokes of the engine and to move the valve to the cut-off position during the two following strokes of the engine.

3. In combination with a double-acting four-cycle explosion-engine, a suitable source of compressed air, passages leading to the respective ends of the cylinder and a valve constructed to assume two consecutive positions which open communication successively with the respective ends of the cylinder, and an intermediate position which cuts off communication with both ends of the cylinder, a cam imparting the three movements to the valve during different strokes of the engine's movements, and means for making and breaking connection between the cam and a driven member of the engine.

The foregoing specification signed at Düsseldorf this 31st day of March, A. D. 1905. 55

VICTOR ERDMENGER.
